UNITED STATES PATENT OFFICE.

ACTON M. HILL, OF HORNELL, NEW YORK, ASSIGNOR TO THE A. J. DEER COMPANY,
INCORPORATED, OF HORNELL, NEW YORK, A CORPORATION OF NEW YORK.

MATERIAL HOLDER FOR SLICING MACHINES.

1,412,244.

Specification of Letters Patent. Patented Apr. 11, 1922.

Application filed September 7, 1920. Serial No. 408,505.

To all whom it may concern:

Be it known that I, ACTON M. HILL, a citizen of the United States, residing in Hornell, in the county of Steuben and State of New York, have invented new and useful Improvements in Material Holders for Slicing Machines, of which the following is a specification.

This invention relates to a material holder for slicing machines which is more particularly designed for gripping the material at one end thereof so that the knife of the machine can cut the material into slices to its very end and thus avoid waste as well as profit in the commercial handling of such materials which are usually sold to the trade in a sliced condition.

The principal object of this invention is to provide a material holder of this character which will reliably hold the material at one end thereof while slices are being cut therefrom at its opposite end.

A further object is to so design the several parts that the same can be operated easily, are not liable to get out of order, can be readily cleaned and are of simple construction.

In the accompanying drawings:—Figure 1 is a sectional front elevation of a slicing machine having a material holder embodying one form of my invention. Figure 2 is a rear elevation of the same. Figure 3 is a horizontal section taken on line 3—3, Fig. 1. Figure 4 is a vertical section on line 4—4, Fig. 2 showing the material grippers in an open position. Figure 5 is a similar view showing the grippers closed. Figure 6 is a fragmentary vertical section, on an enlarged scale, taken on line 6—6, Fig. 1, and showing the manner of securing the fixed jaw of a gripper to the main frame. Figure 7 is a vertical section taken on line 7—7, Fig. 6. Figure 8 is a perspective view of one of the grippers employed in the organization shown in Figs. 1—7. Figure 9 is a sectional front elevation of a slicing machine equipped with a modified form of my improvement. Figure 10 is a rear elevation of the same. Figure 11 is a horizontal section taken on line 11—11, Fig. 9. Figure 12 is a vertical section taken on line 12—12, Fig. 10 and showing the grippers open. Figure 13 is a similar view showing the grippers closed. Figure 14 is a fragmentary sectional perspective view showing the manner of guid-

ing the gripper actuating means on the main frame. Figure 15 is a perspective view of one of the grippers used in the construction shown in Figs. 9—13.

Similar characters of reference refer to like parts throughout the several views. Figure 20 represents the table or carriage on which the article or material to be sliced is supported on its underside while being moved relatively to the knife or cutter 21, 65 which cuts slices successively from the front end of this material. On top of this table is arranged the holder whereby the material to be sliced is grasped at its rear end and held in place while being moved toward and from the cutter, and also while being advanced step by step to the cutting line.

The embodiment of my invention shown in Figs. 1—8 is constructed as follows:—Figure 22 represents a supporting plate which is slidable lengthwise on the upper side of the table and provided adjacent to its opposite longitudinal edges with upright posts or pillars 23. Above the supporting plate and between these posts is arranged a gripper frame which in its preferred form comprises an upright flat backing plate 24 which is arranged transversely of the supporting plate and a rim 25 which projects rearwardly from the marginal parts of this backing plate. The gripper frame is detachably mounted on the posts by seats 26 arranged at one upright edge of the gripper frame and engaging one of the posts and a clamp 27 arranged on the opposite upright edge of the gripper frame and engaging the other post, as shown in Figs. 1—3.

The backing plate of the gripper frame is provided with a plurality of horizontal slots 28 which are arranged in a vertical row and below each of these slots the backing plate is provided with a horizontal row of openings 29 each of which is of forwardly tapering form and provided with an internal screw thread.

Mounted on the gripper frame is a plurality of grippers each of which is constructed integrally of a single piece of spring wire so that the same is of substantially U-shape and forms a pair of jaws which are arranged one above the other and are adapted to close and open for grasping and releasing the material to be sliced. In the preferred construction each jaw comprises a longitudinal arm 31 which is provided at its front end

with an inclined beak 32 projecting toward the beak of the companion jaw and the rear end of each arm is connected with the rear end of the companion arm, by a coil spring 33. These grippers are arranged in parallel horizontal rows, the upper jaws of each row having their arms arranged in one of the slots 28 and the lower arm of each gripper being arranged in one of the openings 29 so that the beaks of the same are arranged in front of the backing plate and the coil springs of the same are arranged in rear of this plate.

The lower arm of each gripper is preferably held in a fixed position on the backing plate by an externally screw threaded forwardly tapering longitudinally split clamping sleeve 34 which surrounds said arm and engages the threads of the opening 28. Upon screwing the clamping sleeve into the opening the tapering formation of the same causes the sleeve to contract and clutch the lower arm of the gripper so that the same is held rigidly against movement. The upper arm of each gripper is normally held in an elevated position by the resilience of the metal of which the gripper is constructed so that the same is open and adapted to receive the material which is to be grasped. Upon depressing the upper jaw while in engagement with the rear end of the material the gripper will be closed and both of its beaks will penetrate the back end of the article and hold the same firmly in engagement with the backing plate of the gripper frame so that the knife can operate effectively on the material and properly cut the last slice therefrom without wastage.

The downward movement of the upper jaws of the several grippers is effected by means which comprise a plurality of shifting bars 35 arranged horizontally and transversely in rear of the backing plate and each bar engaging with the upper side of the upper arms of a horizontal row of grippers, a plurality of upright connecting bars 36 connecting the shifting bars at suitably points, for instance at the central and end portions thereof, loop shaped guides 37 arranged on the central part of the rear side of the backing plate and receiving the central connecting bar 36 and a rotary cam 38 engaging with the uppermost shifting bar and pivoted by a screw 39 to the upper part of the gripper frame to swing in a vertical plane and provided with an upwardly projecting hand lever 40 for manipulating the same. Upon turning the cam so that the same presents the low part of its face to the uppermost shifting bar then the grippers are released and resistance of the same will cause the same to open and upon turning the cam so that the high part of its face engages with the uppermost shifting bar then the several shifting bars will be depressed and the grippers

will be closed and caused to grip the end of the material placed against the backing plate.

This construction of material holder is exceedingly simple, it is efficient in operation, it consists of but few parts which can be easily cleaned and maintained in a sanitary condition, and also produced at comparatively low cost.

In the modified construction of this invention shown in Figs. 9-15 each of the gripper is constructed integrally of a single piece of flat spring metal which is bent into substantially U-shape so as to form two opposing jaws and comprises upper and lower arms 41, 42, upper and lower inclined beaks 43, 44, projecting toward each other from the front ends of said gripper arms and a bow or cross piece 45 connecting the rear ends of said arms. The backing plate 46 of the gripper frame is provided with a plurality of vertical slots 47 which are arranged in parallel horizontal rows. The arms of one of the grippers are arranged lengthwise in each of these slots so that the beaks thereof are in front of the backing plate and the bow thereof in rear of the same, as shown in Figs. 11, 12 and 13. One beak of each gripper is preferably terminated in a pointed end, as shown at 60, and the end of the companion beak is preferably provided with a recess 61, so that when these beaks close upon the material they will obtain a secure hold on the same and retain it reliably in place while the cutter is operating thereon. The lower jaw of each of the grippers is preferably fixed by resting the same against the lower end of the slot 47 through which this gripper passes and the several grippers are held in their operative position relative to the backing plate by grid-like retainers consisting preferably of a plurality of horizontal retaining bars 48 arranged parallel and each secured to the bows of one horizontal row of grippers by means of screws 49, or the like, and two upright attaching bars 50 connecting corresponding ends of the retaining bars and secured to the rim of the gripper frame by screws 51, or similar means.

The upper jaws of the several grippers are moved away from the lower jaws of the same by the resilience of the metal of which the same are constructed and the movement of the upper jaws toward the lower jaw for grasping the rear end of the material which is placed against the backing plate preparatory to cutting the same into slices is produced by means which are constructed substantially the same as these shown in Figs. 1-5, and consist of a plurality of parallel horizontal shifting bars 52 arranged in rear of the backing plate, and each engaging with the upper side of the upper arms of a horizontal row of grippers, an upright connecting bar 53 connecting the central parts of

the shifting bars and guided in loops 54 on the rear side of the backing plate, and a rocking cam 38 pivoted on the upper part of the gripper frame and engaging the uppermost shifting bar and having an upwardly projecting handle 40 for manipulating the same.

I claim as my invention:

1. A material holder for slicing machines comprising a frame, a plurality of grippers mounted on said frame and each having a pair of connected jaws which are relatively movable so as to cause said jaws to grasp the material between or to release the same, and means for actuating said grippers.

2. A material holder for slicing machines comprising a frame, a plurality of grippers mounted on said frame and each having a pair of connected jaws which are relatively movable so as to cause said jaws to open and close, each jaw having an arm and a beak projecting from said arm toward the beak of the companion jaw, and means for actuating said grippers for opening and closing the same.

3. A material holder for slicing machines comprising a plurality of grippers each of which has a pair of cooperating fixed and movable jaws which are integrally connected with each other, a frame provided with a support for the fixed jaw of each gripper, and means for moving the movable jaw of each gripper toward the companion fixed jaw.

4. A material holder for slicing machines comprising a plurality of substantially U-shaped grippers each forming two integral jaws which are adapted to close and open for grasping and releasing the material to be sliced, and means for operating said grippers.

5. A material holder for slicing machines comprising a plurality of substantially U-shaped grippers each forming two integral jaws which are adapted to close and open for grasping and releasing the material to be sliced, a frame upon which one jaw of each gripper is supported in a fixed position, a plurality of shifting bars engaging the other jaws of said gripper, and means for moving said bars.

6. A material holder for slicing machines comprising a plurality of substantially U-shaped grippers each forming two jaws which are adapted to close and open for grasping and releasing the material to be sliced, a frame upon which one jaw of each gripper is supported in a fixed position, a plurality of shifting bars engaging the other jaws of said grippers, and means for moving said bars including a cam movably mounted on said frame and operatively associated with said bars.

7. A material holder for slicing machines comprising a plurality of substantially U-shaped grippers each of which has a sta-

tionary jaw and a movable jaw movable toward and from the companion fixed jaw, a frame on which said fixed jaws are mounted, a plurality of shifting bars engaging with the movable jaws of the several grippers, connecting bars connecting said shifting bars and guided on said frame, and means for actuating said bars.

8. A material holder for slicing machines comprising a plurality of substantially U-shaped grippers each of which has a stationary jaw and a movable jaw movable toward and from the companion fixed jaw, a frame on which said fixed jaws are mounted, a plurality of shifting bars engaging with the movable jaws of the several grippers, connecting bars connecting said shifting bars and guided on said frame, and means for actuating said bars, including a rotary cam pivoted on said frame and engaging one of said shifting bars.

9. A material holder for slicing machines comprising a plurality of substantially U-shaped grippers each of which is constructed integrally of spring metal to form two jaws which are adapted to close and open for grasping and releasing the material to be sliced, and means for actuating the jaws of said grippers.

10. A material holder for slicing machines comprising a plurality of substantially U-shaped grippers each of which is constructed integrally of spring metal to form two jaws which are adapted to close and open for grasping and releasing the material to be sliced, and a coil connecting the jaws of each gripper, and means for actuating the jaws of said grippers.

11. A material holder for slicing machines comprising a plurality of substantially U-shaped grippers each of which is constructed integrally of spring wire to form two jaws, one of which is fixed and the other movable, and a coil connecting said jaws, a frame upon which the fixed jaw of each gripper is mounted, and means for moving the other movable jaw of each of the grippers toward the companion fixed jaw.

12. A material holder for slicing machines comprising a plurality of substantially U-shaped grippers each of which is constructed integrally of spring wire to form two jaws, one of which is fixed and the other movable, and a coil connecting said jaws, a frame upon which the fixed jaw of each gripper is mounted, a frame provided with slots which receive said movable jaws and with internally threaded tapering openings which receive the fixed jaws, and externally screw threaded and longitudinally split clamping sleeves each of which receives the fixed jaw of one of the grippers and engages one of said threaded openings.

13. A material holder for slicing machines comprising a plurality of U-shaped grip-

pers arranged in rows and each having upper and lower jaws, a gripper frame having a backing plate provided with a plurality of vertical slots each of which receives the jaws of one gripper and one end of each of these slots engaging with one jaw of the respective gripper, and means for actuating the other jaw of each gripper.

14. A material holder for slicing machines comprising a plurality of U-shaped grippers each having two jaws and a bow connecting the rear ends of said jaws, a retaining bar on which said bows are mounted, and means for opening and closing the jaws of the grippers.

ACTON M. HILL.
